SHAVING IMPLEMENT

Henry T. Schiff, Chicago, Ill.

Application March 11, 1938, Serial No. 195,338

1 Claim. (Cl. 30—43)

My invention relates to a shaving implement adapted for use as a dry shaver of the motor driven type.

Among the objects of my invention are to provide a shaving implement adapted to give as close a shave as desired by the user with positive clipping action and without pulling hair or causing a burning sensation; to create a shaving implement having balanced resilient members positioned at both sides of the driving shaft for permitting the inner movable member to move transversely with respect to the stationary outer member without friction, said resilient members being positioned against movement at their lower ends and contacting the movable member with their upper ends so as to oscillate therewith and insure an evenly directed pressure of the inner member on the outer member; to create a shaving implement which is substantially non-clogging, its parts being so arranged that there are no portions for the retention of clipped hair; to supply a shaving implement having in effect a double head with four shaving surfaces, its inner movable member having a pair of rows of teeth, and such other objects, advantages and capabilities as will later more fully appear and which are inherently possessed by my invention.

While I have shown in the accompanying drawings a preferred embodiment of my invention, yet I wish it understood that the same is susceptible of modification and change without departing from the spirit of my invention.

Fig. 1 is a perspective view of my shaving implement with a portion broken away to show the motor; Fig. 2 is a perspective view of the head of my shaving implement; Fig. 3 is a detail view of the inside of outer stationary member of the head, and Fig. 4 is a similar view of the inner movable member; Fig. 5 is a sectional view of the upper portion of my shaving implement and Fig. 6 is a detail view of the inside of my casing; Fig. 7 is an enlarged detailed sectional view and Fig. 8 is a view drawn on line 8—8 of Fig. 7.

The embodiment selected to illustrate my invention comprises a hollow casing 10 preferably of two parts in which is arranged in any suitable manner an electric motor 11 adapted to be connected to an electrical source of supply by lead wires 12. The motor 11 has a driving shaft 13 ending in an extreme eccentric 14 adapted to engage a head 15.

My head 15 comprises an outer stationary member 16 and an inner movable member 17.

The outer member 16 has a pair of oppositely disposed upwardly extending portions 18, bent at their upper ends at substantially right angles thereto and extending integrally inwardly to form a pair of substantially flat top portions 19 connected by a U shaped or channel portion 20. A plurality of spaced and substantially parallel slits 21 are formed longitudinally across most of each of the top portions 19; said slits continuing at the outer edges of the top portions 19 to extend downwardly a short distance on each of vertical portions 18.

The inner member 17 is substantially channel shaped to fit and slidably move on inner side of U shaped channel portion 20 of outer member 16. The outer edges 40 on each side of said inner member 17 are extended at substantially right angles and have a plurality of spaced serrations or teeth 22. A centrally disposed aperture 23 is cut in movable member 17 to receive the end 20 of shaft 13 with its eccentric 14.

Adjacent the top of my casing 10 an aperture 24 is provided through which the driving shaft extends to the head 15. At both sides of said aperture 24 and spaced therefrom are a pair of oppositely disposed slots 25 each having a closed bottom 26 and an open top 27. The slots 25 are tapered so that they are larger at their top portions 27 than at the bottoms 26. In each of said slots is positioned a resilient member 28 of such size that its bottom end is positioned against movement in the smaller bottom portion 26. The top end of each resilient member 28 bears against the outer side of movable member 17. As the movable member 17 moves the wider top portion 35 of slot 25 permits the top portion of resilient member 28 to move with the movable member 17 to thus prevent friction and to retain perfect balanced pressure at all times.

To attach my head 15, I provide a pair of oppositely disposed slots 29 within casing 10 and on opposite sides thereof. Within said slots 29 are perfectly fitted nuts 30 having a screw threaded aperture 31. A pair of clamping members 32 adapted to fit within notches 37 on either side of casing 10 also have a screw threaded aperture 33. A bolt 38 passes through apertures 33 and 31. The clamping members 32 each have a slight inturned flange 34 and a center member 35 adapted to engage the top of U shaped channel 20 of outer member 16. A pair of spaced extensions 36 on either side of center member 35 are adapted to fit under top portions 19 of outer member 16.

My shaving implement in use provides four

- shaving surfaces so as to give the user as close a shave as he desires with positive clipping action as well as greater convenience. Because my eccentric is farther off center than heretofore my device has greater speed. My balanced frictionless pressure construction secures constant and uniform operation without pulling. With my head having an open channel and no closed portions, clogging is impossible.
- 5 The outer member 16, on which is positioned inner member 17, is held by clamping members 32 above the upper end of casing 10 and leaves a space 39 between the head 15 and casing 10 for the free exit of cut hair.
- 10 Having thus described my invention, I claim:
- A shaving implement comprising a casing, a stationary member having slits attached to said casing, a movable member having teeth positioned against said stationary member, a driving shaft 20 having an eccentric adapted to contact said movable member so that upon movement of said shaft the teeth of the movable member operate transversely to the slits in said stationary member, said casing having a pair of slots on opposite sides 25 of said driving shaft, said slots having a narrow closed bottom and tapering upwardly and outwardly to a wider open top, a pair of resilient members positioned in said slots, the bottoms of
- said resilient members held in fixed position by the narrow bottoms of said slots, the tops of said resilient members contacting the outer side of said movable member and permitted by the tapering portion and the wider open top of the notches to travel with said movable member and apply continuous balanced frictionless pressure on the movable member against the stationary member, said casing having adjacent its upper sides a pair of oppositely disposed slots, a pair of nuts fitted 10 within said slots, said nuts each having a screw threaded aperture, said casing having on its upper side portions a pair of oppositely disposed notches, a pair of clamping members each having body portions adapted to fit within each of 15 said notches, said body portions each having a screw threaded aperture, said clamping members each having an inturned flange adapted to engage the stationary member, and screw threaded bolts adapted to pass through the screw threaded 20 apertures of the body portions of the clamping members and the nuts to hold the clamping members, the stationary member, the movable member and the resilient members against accidental displacement and to retain the resilient 25 members in normal pressure exerted position against the movable member.

HENRY T. SCHIFF.
